UNITED STATES PATENT OFFICE.

GEORGE S. THOMPSON, OF PITTSBURGH, PENNSYLVANIA, ASSIGNOR TO JAMES H. MATTHEWS & COMPANY, OF PITTSBURGH, PENNSYLVANIA, A CORPORATION OF PENNSYLVANIA.

MACHINE FOR MARKING CYLINDRICAL ARTICLES.

1,386,812.

Specification of Letters Patent. Patented Aug. 9, 1921.

Application filed February 2, 1921. Serial No. 441,787.

To all whom it may concern:

Be it known that I, GEORGE S. THOMPSON, residing at Pittsburgh, in the county of Allegheny and State of Pennsylvania, a citizen of the United States, have invented or discovered certain new and useful Improvements in Machines for Marking Cylindrical Articles, of which improvements the following is a specification.

10 My invention relates to improvements in machines for marking cylindrical articles. I have developed it in a machine for printing legends upon powder kegs, and I shall describe the machine so developed as an embodiment of the invention; but it will be understood that the invention is applicable to machines for marking cylindrical articles generally, without limitation as to size, material, or purpose served by the articles 15 marked, and to machines for marking generally, without limitation to printing specifically.

In the accompanying drawings, Figure I is a view in side elevation of a machine of 20 my invention for printing legends on powder kegs; Fig. II is a view of the same machine in end elevation; Fig. III is a view in plan from above; and Fig. IV is a view in longitudinal and vertical section on the plane indicated by the dotted line IV—IV, Fig. III, 25 showing a detail of construction.

In a suitable bed 1 are journaled two parallel shafts 2 and 3 which carry concentric work-sustaining surfaces. In this instance these surfaces conveniently take the form of drums 4, a pair of drums being 30 rigidly mounted on each of the two shafts, and the drums upon the two shafts being conveniently arranged one opposite another, 35 as shown.

A shaft 5, conveniently journaled in bed 1 parallel with and intermediately placed between shafts 2 and 3 constitutes the power shaft. It may be rotated in any suitable 40 manner; the drawings show a crank 6, by which shaft 5 may be manually rotated. Suitable provision is made for rotating drums 4 in uniform direction in response to rotation of shaft 5. This interposed mechanism 45 conveniently consists of a countershaft 7 journaled in frame 1 parallel with and adjacent shaft 5, of intermeshing pinions 8 and 9 carried by shafts 5 and 7, of sprocket

wheels 10 and 11 carried by shafts 7 and 2 and 3, and of sprocket chain 12 engaging the 55 sprocket wheels.

The dotted circle K in Fig. I indicates the outline of a powder keg to be marked, placed in the machine in position for marking. It rests, be it observed, by gravity on the four 60 drums 4 and as they turn (in uniform direction—anti-clockwise, say) the powder keg turns (clockwise) at a peripheral speed equal to that of drums 4.

Pivoted in suitable bearings in frame 1 65 (conveniently on shaft 2), so as to swing in a plane perpendicular to the cylindrical axis of powder keg K when in place, is a lever 13. The upwardly extending arm of lever 13 carries the printing wheel 14 (the lever 70 is, to that end, preferably bifurcated, as best shown in Fig. II); the downwardly extending arm of lever 13 is engaged by lever swinging instrumentalities. A spring 15 anchored to frame 1 and secured to the lower 75 end of lever 13 tends always (the parts being assembled as shown in Fig. I) to cause the lever to turn on its pivot in anti-clockwise direction. A cam 16 keyed to shaft 7 engaging a link 17 connected to the lower 80 end of lever 13 is effective, as shaft 7 turns, intermittently to swing lever 13 clockwise (Fig. I) against the tension of spring 15. Link 17 it will be observed extends in 85 diametrical line with respect to shaft 7; accordingly it is slotted, as shown in Fig. I, to straddle and to be capable of longitudinal movement free of interference with shaft 7, and is provided at its end with a cam-engaging roller 18. When lever 13 is free to 90 respond to spring 15 (a keg K being in place), printing wheel 14 is held tangent to the keg, and the tension of the spring is effective to cause the wheel 14 to bear upon the keg with substantial pressure; when 95 lever 13 is by cam 16 swung in clockwise direction, the printing wheel 14 is remote and kegs may be removed and replaced.

Rotation is imparted from shaft 5 to printing wheel 14 through suitable instrumentalities. Explanation has already been made, that shaft 2 (upon which lever 13 conveniently is pivoted) is rotated through certain described instrumentalities from shaft 5. Shaft 2 may be provided with a sprocket 100 wheel 19 and printing wheel 14 may be pro-

vided with a sprocket wheel 20, and a sprocket chain 21 may be provided engaging both.

The several pinions and sprocket wheels 5 now described (8, 9, 10, 11, 19, and 20)—or their equivalents—are advantageously so proportioned as to accomplish these several ends; (1) Equal peripheral speed of the two 10 rotating members, the keg and the printing wheel. This is an essential condition, and it is brought about under circumstances which for other reasons are desirable, and which I now proceed to enumerate. (2) Printing wheel 14 is of greater circumference than 15 the keg K to be marked, and cam 16 is so proportioned that the printing wheel during one complete rotation will turn in tangency with the keg throughout one rotation of the keg, and during the remaining portion of 20 the time of its complete rotation, will be retracted, to allow removal and replacement of kegs. (3) Drums 4 are conveniently of equal diameter with the kegs to be marked, and accordingly of somewhat smaller diameter 25 than printing wheel 14; they turn the kegs at equal peripheral speed with themselves. Accordingly they turn at the same peripheral speed with printing wheel 14, and therefore at a carefully calculated and 30 faster rate of rotation. (4) Shaft 5 turns through two rotations to effect one complete rotation of printing wheel 14.

Mounted for cooperation with the marking drum 14 is an inking device; it appears 35 in Figs. I and III of the drawings, arranged to the right of drum 14, and bears the general reference numeral 22. It is carried, as will be seen, on a bracket borne by lever 13. This inking device is of a style already well 40 known, it is incidental merely to my invention, and I therefore do not describe it in detail. Suffice it to remark of the inking device that it includes feeding rolls which, as indicated in Fig. I, may be driven by the 45 same sprocket chain 21 which turns drum 14.

Means may be provided for the arrest 50 of rotation at a suitable moment, after each keg in turn has been marked and when the printing wheel has receded from tangency with the keg. In this connection it may be remarked that, a fifth condition of mechanical structure is advantageous, namely (5), that shaft 7 shall rotate once while shaft 5 rotates twice, and accordingly that 55 the rate of rotation of shaft 7 and of printing wheel 14 shall be identically the same (the rate of rotation of shafts 2 and 3 being, as has already been said, somewhat faster. These means for arresting rotation however 60 lend themselves peculiarly to a hand driven machine; if power were applied to drive the machine other or additional braking or stopping mechanism would preferably be employed. The provision of suitable mechanism 65 (once the need for it is indicated)

will readily be adopted by an engineer engaged in designing a machine.

With the hand driven machine illustrated, a simple and convenient stopping mechanism consists of a notched disk 23 keyed to 70 shaft 7, and a lever 24 provided with a detent 25. The lever is so weighted that it tends always to swing in a direction to bring the detent into engagement with the notch in the periphery of disk 23. The detent 75 always bears upon the periphery of the disk, and with the completion of each rotation of shaft 7 it enters the notch and stops the machine. Lever 24 may be swung manually to release the lock and to allow 80 the rotating parts to turn again.

Operation is as follows: Beginning with the machine in locked position, with detent 25 in engagement with the notch in the rim of disk 23, cam 16 is, at that moment in the course of rotation of shaft 7, bearing upon roller 18 in the end of link 17; is exerting tension through link 17 and is holding lever 13, against the tension of spring 15, in its retracted position, with 85 printing wheel 14 swung to the right (Fig. I) and free of tangency with keg K. The parts being in this position, a keg K already marked may be removed and may be replaced by another and unmarked keg. 90 When the unmarked keg has been placed the operator will first swing lever 24, unlocking shaft 7; he then will turn shaft 5, and in so doing will set in motion all the correlated parts described above. The following motions will then be achieved in sequence: (1) Keg and printing wheel will begin to turn at equal peripheral speed and will continue to turn through one complete rotation of the printing wheel—something 100 more than one complete rotation of the keg. (2) Soon after rotation begins the high part of cam 16 will pass from engagement with roller 18 of link 17; spring 15 will then become effective to swing lever 13 and 105 to bring printing wheel 14 to bear with suitable pressure upon keg K. The tangency so established will continue through one complete rotation of the keg. Meanwhile the inking device will function, and 110 the wheel will impart to the keg one complete impression from the type or printing face with which its periphery is equipped. (3) At the completion of one complete rotation of the keg while in tangency with 115 the printing wheel, the high part of cam 16 will come again into engagement with roller 18 of link 17, and immediately lever 13 will swing clockwise (Fig. I) and the printing wheel will be retracted from the keg. (4) Detent 25 will then fall into the notch in disk 23 and the machine will thus be 120 brought to a stop. The now marked keg may be removed, and the cycle of operation 125 repeated.

As I remarked at the beginning the powder-keg marking machine now described is but one embodiment of my invention; the invention is applicable to the marking of 5 cylindrical articles, regardless of size, and to the application of marks to the articles, whether by printing or otherwise. The invention, it will be understood, is not limited to details of mechanism, and will be 10 practised in the use of instrumentalities defined in the ensuing claims.

I claim as my invention:

1. In a machine for marking cylindrical articles, the combination of a set of drums 15 rotatable in stationary bearings and adapted to support an article resting upon them and by rotation to effect rotation of such article, a printing drum rotatable in bearings which are reciprocable relatively to the 20 stationary bearings named, said printing drum, by virtue of such reciprocity of its bearings, being movable to and from a position of tangency with an article of given size resting upon said stationary bearings, the said printing drum being of greater 25 circumference than the article with which it is adapted to make contact as aforesaid, means for rotating all of said drums continuously and in uniform direction and at 30 equal surface speeds, and for reciprocating

said printing drum at predetermined intervals as rotation progresses, the reciprocating feature of the means last named effecting reciprocation of the printing drum from and return to such position of tangency 35 with an article under treatment, during so much of a rotation of the printing drum as the interval by which its circumference exceeds the circumference of the article under treatment.

2. In a machine for marking cylindrical articles, means for causing an article to be marked to rotate on its cylindrical axis, a mark-imparting rotary cylinder of greater diameter than said article, means for rotating said cylinder in opposite direction to and at equal peripheral speed with the article, means for causing the cylinder to bear tangentially as rotation progresses upon the article, intermittently acting means for withdrawing said cylinder from such tangency, and locking means becoming effective in sequence after the cylinder-withdrawing means last defined, substantially as described.

In testimony whereof I have hereunto 55 set my hand.

GEORGE S. THOMPSON.
